Primary Examiner — Robert M Spear*Assistant Examiner* — John Voytek*(74) Attorney, Agent, or Firm* — Fay Sharpe LLP(57) **CLAIM**

The ornamental design for a tire tread, as shown and described.

DESCRIPTION

FIG. 1 is a perspective view of the tire tread of the present application;

FIG. 2 is a side view thereof;

FIG. 3 is an enlarged partial side view thereof;

FIG. 4 is a front view thereof; and,

FIG. 5 is an enlarged partial front view thereof.

The broken line showings of the sidewall, inner bead, and the peripheral boundary between the tire tread and the sidewall are included for the purpose of illustrating environment and form no part of the claimed tire tread. The tread pattern is understood to repeat uniformly throughout the circumference of the tire.
